ELECTRICAL INDICATING INSTRUMENT

Leslie H. Middleton, La Crosse, Wis., assignor, by
mesne assignments, to Moto Meter Gauge &
Equipment Corporation, a corporation of Dela-
ware (1935)

Application June 22, 1934, Serial No. 731,968

12 Claims. (CL. 171—95)

This invention relates to electric gasoline gauge heads comprising a pointer type galvanometer responsive to a float controlled rheostat for indicating liquid level, particularly in gasoline tanks 5 of automotive vehicles, such as shown and described in Cheney Patents No. 1,745,603 granted February 4th, 1930, and No. 1,753,402 granted April 8th, 1930, on which the present invention is an improvement.

10 Objects of this invention are to strengthen the construction of gauge heads of this character, to increase the torque upon the pointer whereby the effect of road shocks and vibration thereon is decreased; to improve the magnetic circuit, and to 15 facilitate adjustment and calibration of the instrument.

Other objects will become apparent as the following description proceeds, with reference to the accompanying drawing, in which

20 Figure 1 is a front elevation of the instrument with the dial removed;

Figure 2 is an inverted plan;

Figure 3 is a rear elevation; and

25 Figure 4 is an expanded perspective view of the flux distributing plate.

The frame of the instrument comprises a metal base plate 6 having upwardly and laterally extending wings 7 and 8 on which the magnet coils 9 and 10 are mounted, and lower arms 11 and 12 30 which are bent forwardly and then upwardly to receive and support the dial 15. Between the arms 11 and 12 a loop 16 is bent forwardly and upwardly to support the front bearing of the armature shaft.

35 A strip of fiber insulation 17 is mounted in back of the frame base plate 6, between lugs 18 bent back therefrom. A metal backing plate 19 has lugs 20 bent forwardly around the insulation strip 17, and has lateral wings 21 and 22 overlying 40 the base plate wings 7 and 8.

The coil 9 is a constant coil having higher resistance and less magnetic strength than the variable coil 10. These coils each have an iron core in the form of a spool, which is mounted on a 45 bracket 23 of a box corner type. The stem 24 of the core spool extends through an opening in the upstanding flange 25 of the bracket, and is upset or peened to secure a rigid mounting thereon. The inner disk of the spool is slotted and the 50 metal therebetween bent inwardly to form pole tips 26.

The flux distributing plate 27 shown in Figure 4 is mounted on the plate 6 with its branches overlying the wings 7 and 8 of the frame base 55 plate. The base 28 of the bracket of the constant

coil 9 is placed over the flux distributing plate, and a screw 29 inserted from the back of the instrument passes through registering openings in the wing 21, the wing 7, the plate 27 and the bracket base 28, rigidly securing the constant 5 coil 9 in position with its core aligned with the armature shaft.

The coil 10 however, is intended to be adjusted and for this reason the holes in the wing 22, the wing 8, and the branch 30 of the flux distributing 10 plate are elongated to form slots 35, and the screw 32 passes through these registering slots into the base 33 of the bracket for the coil 10.

The flux distributing plate has a movable extension, the base 34 of which overlies the branch 15 30 and underlies the base 33, and the screw 32 passes therethrough also. This extension has an ear 36 caught between the spool of coil 10 and the bracket flange 25, and through which the stem 24 passes, so that the extension 34 is rigid with the 20 base 33.

Another branch of the flux distributing plate has an integral extension 37 which is turned up 25 toward the outer pole of the constant coil 9. A third branch 38 is turned up at the bottom of 25 the instrument, between the sides of the loop 16, adjacent to the armature.

The armature 40 comprises a double segment of iron rigidly secured to a spindle 41 journaled in a 30 clock bearing carried by a screw 42 which extends through the plate 6 and the flux distributing plate 27. The front end of the armature spindle is journaled in a clock bearing 43 fixed in the loop 16. A pointer 44 and a counterweight 45 therefor are also rigidly secured to the spindle 41. 35

The clock type bearings are long and rugged, and avoid difficulties of the old conical pointed pivots. The parts are held in constant and permanent alignment, irrespective of magnetic and mechanical forces acting upon the spindle and 40 bearings.

A loose fly-wheel 46 or inertia dampener, is mounted on the spindle 41 between two collars 47 slightly spaced therefrom. The center hole in the fly-wheel 46 is slightly larger than the spindle, 45 so that frictional engagement with the shaft and collars is the only connection to the spindle.

As the pointer must overcome the natural inertia of the fly-wheel, which opposes any movement thereof, the same is damped to avoid 50 vibration thereof due to road shocks and jarring.

The lower arms 11 and 12 of the base plate 6, which form posts to support the dial plate 15, are entirely separate and distinct from the gauge movement itself, thereby avoiding any possibility 55

of dial movement being transmitted to the gauge movement, and preventing sticking and binding.

An upper contact stud 48 passes through the top of the insulating strip 17, and a lower or central contact stud 49 passes through the frame base plate 6 and the strip 17, the head of the stud being insulated from the plate 6. Contact tabs 50 are mounted under the heads of each of these studs, and in electrical contact therewith.

The constant coil 9 has an end grounded to the frame, and the other end connected by one of the tabs 50 to the central contact stud 49. The variable coil 10 is connected to the tank fitting rheostat one end of which is grounded.

As the current is gradually increased through the variable coil 10 due to filling the gas tank and cutting out resistance in the tank rheostat, the field strength from the tips 26 of the variable coil 10 is increased, and this tends to move the armature from a position opposite the constant coil 9 to a position opposite the variable coil 10.

The pole tips 26 are of advantage in that they are in close proximity to the armature 40, which serves to concentrate the flux from each coil at these tips 26. When the tank fitting float rheostat is in the "empty" position, there is no current flowing through the variable coil 10 and the current flowing through the constant coil 9 generates a field concentrated at the tips 26, tending to hold the armature in zero position.

The variable coil 10 has corresponding pole tips which concentrate the field thereof in the same manner. The strength of the field generated by this variable coil 10 is dependent upon the current therethrough, in turn dependent upon the rheostat as controlled by the float in the tank.

These pole tips 26 therefore, serve to concentrate these various field forces in the path of the armature. Without these tips 26, the poles would have to be very close to the armature, to concentrate the flux for the torque necessary to stabilize the pointer under road shocks and vibrations.

The flux distributing plate forms a complete iron circuit for the magnetic flux, and incloses both of the coils and the armature. The branch terminating in the bendable tip or integral extension 37, is associated with the outer pole of the constant coil 9.

The movable extension 36 which is riveted on to the outer pole of the variable coil 10, having its base 34 movable with respect to the slot 35 in the flux plate proper, results in a sliding connection between the iron core of the variable coil 10, and the flux distributing plate, but a considerable leakage passes between the core of the constant coil 9 and this plate, at the bendable tip 37.

The central arcuate branch 38 is associated with the armature 40, and has its tip curved to approximate the path of this armature, so that there is no change in the air gap between the armature and this flux plate, and no change in the field strength, at any point in the armature path.

In assembling the instrument, the constant coil 9 is fixed solid in a predetermined definite position on the base plate 6, as by means of a jig. The variable coil 10 is set in an arbitrary position during assembly.

The gauge is calibrated on zero by bending the tip 37 of the flux distributing plate upwards or sideways through a range of about one sixteenth 75 of an inch with respect to the outer end of the

iron core spool of the constant coil 9. Thus the zero calibration is effected by bending back and forth the iron circuit connecting it to the main flux circuit.

The screw holding the variable coil in position 5 passes through a slot in the base plate and flux distributing plate, so that this coil is adjustable for rotation about this screw and also inwardly and outwardly, so as to obtain the desired overall range on the instrument in connection with the 10 adjustment of the constant coil above referred to. The pointer position when all resistance is cut out from the tank rheostat is adjusted particularly by the position of the variable coil.

The scale range adjustment is made by loosening the screw 32 and moving it along the slots 35, thus moving the variable coil 10 back and forth from the armature to vary the strength of the flux; and also by swiveling about the screw 32 as a pivot, to vary the direction of the flux, 20 after the lateral adjustment has been obtained.

The "full" position of the pointer and the scale characteristics are adjusted by bending the center branch 38 of the flux distributing plate toward or away from the armature, to strengthen 25 or weaken the flux. At the same time, bending the corners of this branch 38 in or out permits a slight flux directional calibration means for correcting scale errors.

The constant coil 9 may be swung about the 30 mounting screw 29 as a pivot, to adjust the magnetic field in relation to the field of the variable coil 10, to enable the "empty, 1/4, 1/2, 3/4, full" positions of the pointer to be calibrated at the desired points on the scale.

While it is essential to move the variable coil 10 to calibrate the gauge, the constant coil need not be moved.

The double pole tips in combination with one swiveling adjustable coil and one coil both swiveling and laterally adjustable enable four pole tips to be variable in position with respect to the armature and the two pairs are also variable with respect to each other. Thus these four flux paths can be adjusted to give any desired scale calibration.

It should be noted that in addition to the flux strength adjustment of the distance of the coil from the armature, a flux directional distribution adjustment is provided, by the pivotal movement of either of the coils, and by the corner bending of the flux distributing plate tips 37 and 38.

The structure as here described enables the manufacture of a neat, positive, and accurate gas 55 gauge head, which quickly and positively follows any change in the resistance of the tank fitting rheostat, and by the concentration of field strength has ample power to cause the pointer to take a true reading position without lag, and 60 has sufficient power to overcome pivot friction ordinarily met with in a gauge of this type. Accurate readings are thus obtained both with an ascending or descending pointer.

What I claim is:

1. In an electrical instrument, an armature, a frame, a coil having a constant field excitation and a coil having a variable field excitation, said coils being located on said frame at an angle to each other, an inflexible mounting for said coil 70 having the constant field excitation, and adjustable means for moving said coil having the variable field excitation axially toward and away from said armature, and also in a plane perpendicular to the axis of said armature.

2. In an electrical instrument comprising a pointer type galvanometer responsive to a float controlled rheostat for indicating gasoline tank level of automotive vehicles, the combination of 5 a frame, a coil of constant excitation and a coil of variable excitation located on said frame at an angle to each other, means for maintaining said coil of constant excitation in fixed position on said frame, means for calibrating the gauge 10 on zero without moving said coil of constant excitation, and adjustable means for moving said coil of variable excitation to alter said angle and thereby adjust the scale range of said gauge.

3. In an electrical instrument, a frame, a coil 15 adapted to produce a constant field of force and a coil adapted to produce a variable field of force, said coils being located on said frame at an angle to each other, said coil adapted to produce a variable field of force having a slidable pivotal 20 mounting on said frame.

4. In an electrical instrument, a frame, a coil having means for exciting its winding to produce a constant field, and a coil having means for exciting its winding to produce a variable field, located on said frame at an angle to each other, a flux distributing plate having portions adjacent both of said coils, and means for adjusting 25 the area of said plate.

5. In an electrical instrument, an armature, 30 a frame, a coil having means for exciting its winding to produce a constant field, and a coil having means for exciting its winding to produce a variable field, located on said frame at an angle to each other, a flux distributing plate having 35 portions adjacent both of said coils, adjustable means for moving said variable coil with respect to said armature, and means for altering the relation of the adjacent portion of said flux distributing plate to said constant coil.

40 6. In an electrical instrument, a frame, an armature, a coil having means for exciting its winding to produce a constant field, and a coil having means for exciting its winding to produce a variable field, located on said frame at an 45 angle to each other, a flux distributing plate having portions respectively associated with each of said coils and said armature, and means for respectively adjusting the relation of said portions to said constant coil and armature, and

means for adjustably mounting said variable coil on said frame for movement with respect to said armature.

7. In an electrical instrument, an armature, a frame, a coil having means for exciting its winding to produce a constant field, and a coil having means for exciting its winding to produce a variable field, located on said frame at an angle to each other, a flux distributing plate associated with said coils and armature, and adjustable 10 means for moving one of said coils with the associated portion of said plate relative to said armature and to the remainder of said plate. 5

8. In an electrical instrument, a frame, an armature, a coil of constant excitation and a coil 15 of variable excitation located on said frame at an angle to each other, one of said coils having a pole tip inclined toward said armature in the plane thereof.

9. In an electrical instrument, a frame, an armature, a coil of constant excitation and a coil 20 of variable excitation located on said frame at an angle to each other, one of said coils having a spool core, portions of said core being bent inwardly in the plane of said armature, and means 25 for adjusting the position of said coil for altering the flux.

10. In an electrical instrument, a frame, an armature, a coil of constant excitation and a coil 30 of variable excitation located on said frame at an angle to each other, one of said coils having a spool core, portions of said core being bent inwardly in the plane of said armature to form 35 pole tips, a flux distributing plate between said coils and frame, adjustable means for moving said variable coil thereon with respect to said armature, said flux distributing plate having bendable branches respectively associated with said constant coil and said armature.

11. In an electrical instrument, a pair of coils 40 mounted at an angle to each other, one of said coils having a bent pole tip for concentrating the flux thereof.

12. In an electrical instrument, an armature and a coil having a spool core, a portion of the 45 flange of said spool being bendable in the plane of the armature for altering the flux.

LESLIE H. MIDDLETON.
